UNITED STATES PATENT OFFICE.

JOSEPH R. BLAINE, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

PRINTING PRESS.

Application filed May 3, 1924. Serial No. 710,759.

This invention relates to a printing press and more particularly to the feeder pile frame thereof and its relation to the main frame and parts carried thereby.

5 It is desirable to have the feeder pile as close to the impression cylinder as possible so that the travel of the sheet from the pile to the cylinder is a minimum and the problem of controlling the sheet is lessened 10 accordingly. It is also desirable to handle fed sheets positively and where the distance is relatively short such positive handling of sheets is facilitated.

In presses of considerable size a relatively 15 large amount of floor space is required. Especially is this so because heretofore a space of about two and one-half or three feet has been left between the main frame of the press and the feeder pile frame to permit an operator to enter between said frames to facilitate the operation of "make ready" 20 on one or more of the parts of the printing couple. Such accessibility is essential.

Therefore one object of my present invention is to reduce the space between the feeder pile frame and the impression means to a minimum so that the press and feeder frame may occupy a minimum amount of floor space and facilitate the control of fed 25 sheets and at the same time provide an arrangement to make simple the operation of "make ready".

Another object is to provide a feeder pile frame which may be readily moved away 30 from and toward the main frame and also provide simple means for propelling said feeder pile frame to facilitate the operation of "make ready".

These and other objects are accomplished 35 by means of the arrangement disclosed on the accompanying sheets of drawings, in which—

Figure 1 is a fragmentary side elevation of a printing press embodying my invention; and

Figure 2 is a fragmentary sectional view taken in the plane of line 2—2 of Figure 1.

The various novel features of the invention will be apparent from the following 50 description and drawings, and will be particularly pointed out in the appended claims.

Referring to the figures of the drawings, it will be noted that the printing press has

a main frame 10 in which an impression cylinder 11 is rotatably mounted, said cylinder cooperating with a horizontally reciprocating flat bed 12. Sheet material from the feeder pile 13 is fed sheet by sheet from said pile over a feed board 14 to the impression cylinder 11 preparatory to the sheets receiving an impression. As pointed out hereinabove, it is desirable to reduce the distance between the feeder pile and the impression means to a minimum to facilitate the handling of sheets. At the same time it is necessary that some provision be made to facilitate the operation of "make ready" not only of the cylinder, but of the type bed. Heretofore a space of about two and one-half to three feet has been left between the main frame of the press and the feeder pile frame to permit the entry of an operator therebetween to "make ready" in connection with the type bed. Such, however, requires considerable travel of the sheets from the sheet pile to the impression means and at the same time the floor space of the unit is naturally large.

To overcome the objectionable features and apparent inconsistencies above enumerated, I have provided an arrangement in which the feeder pile frame, designated generally by the reference character 15, when in operative association with the main frame 10 of the press occupies an immediate adjacent position, and in fact, telescopes with said main frame for reducing the distance between feed pile 13 and the impression cylinder 11 to a minimum. The feeder pile frame 15 includes longitudinally extending members 16 and 17 arranged in pairs and at their front ends connected to a cross shaft 18, each pair at its rear end being connected to an associated shorter shaft 19. Extending vertically upwardly from suitable socket portions 20 in the frame members 17 are corner posts 21 which are connected at their upper ends by upper framing 22. A feed pile table 23 suitably supported upon I-beams 24 is elevated step by step through any suitable mechanism, including a link 25 carried by the feeder pile frame and actuated from a lever 26 on the main frame of the press.

As shown in full lines in Figure 1, the feeder pile frame is in its operative posi-

tion with respect to the main frame 10 and is locked in said position by hooks, only one of which, 27, is shown, said hook being releasably locked to a projection 5 28 on the main frame and being supported in a bracket 29 carried by the associated corner post 21. A support 30 for the link 25 extends from the bracket 29. By merely raising the locking hooks 27 10 out of locking engagement with the projections 28 the feeder pile frame with all of the mechanism carried thereby, as a unit, may be bodily moved entirely away from said main frame so that an operator may 15 freely pass from either side of the press between the main frame 10 and feeder pile frame 15 to "make ready", or to work on other parts accessible from such position. In view of the fact that the rod 25 terminates 20 in a shoe 31 having a flat surface which engages a roller on a lever arm 32 which is operatively connected to the actuating lever arm 26, the operative association between the reciprocating rod 25 and its 25 actuating mechanism, including lever arm 32, is broken without requiring any attention. Likewise, when the feeder pile frame is moved back into operative association with the main frame 10 the shoe 31 is 30 pressed into butt engagement with the lever arm 32 as the locking dog 27 automatically passes into locking engagement with its associated lug 28.

In connection with quickly and easily 35 moving the feeder pile frame 15 to and from the main frame 10, I have provided an efficient and simple power transmission mechanism arrangement. Among other things it includes a drive shaft 33 which is journaled 40 in and connects frame members 16. To one end of the drive shaft 33 is secured an operating hand wheel 34 for manual operation. However, it will be appreciated that if it is desired to operate the shaft 33 by 45 motor such may be readily done. Secured to the shaft 33 and spaced apart, are pinions 35 which mesh with driving gears 36 loose on the shaft 18. The gears 36 are integrally formed with traction wheels 37 50 which rest upon and are adapted to travel on supporting rails 38. Mounted upon the shorter shafts 19 also are wheels 39 which ride on the rails 38. To make more positive the travel of the feeder pile frame 55 the driven gears 36 mesh with racks 40 formed at one side of each of the rails 38. From this arrangement it is apparent that if the locking hook or hooks 27 are raised the feeder pile frame with its pile platform 60 and other parts, as a unit, may be readily moved entirely away from said main frame by merely rotating the wheel handle 34, power being transmitted through the shaft 33 and gears hereinabove described. 65 In a similar manner the feeder pile frame

may be easily and quickly returned to its normal operative position with respect to the main frame 10 of the press.

It is my intention to cover all modifications of the invention falling within the 70 spirit and scope of the following claims.

I claim:

1. In a printing press, the combination of a main frame, a printing couple carried thereby, a feeder pile frame, a pile platform carried thereby, said feeder pile frame with its pile platform as a unit being bodily movable entirely away from said main frame in a direction longitudinally with respect to said main frame to render parts 75 accessible for "make ready", and power mechanism for moving said feeder pile frame. 80

2. In a printing press, the combination of a main frame, a printing couple carried thereby, a feeder pile frame movably mounted with respect to said main frame whereby an operator may pass between said main and feeder pile frames from either side 85 of the press for "make ready", and power means carried by said feeder pile frame for propelling the latter. 90

3. In a printing press, the combination of a main frame, a printing couple carried thereby, a feeder pile frame movably mounted with respect to said main frame, means for releasably locking said feeder pile frame to said main frame, said feeder pile frame when moved away from said main frame providing a continuous space between 95 said frames to permit an operator to move between said frames from either side of the press, and power means carried by said feeder pile frame for propelling the latter. 100

4. In a printing press, the combination of a main frame, a printing couple carried thereby, a feeder pile frame, a pile platform carried thereby, a power transmitting member carried by said feeder pile frame for actuating said pile platform, a power transmitting member carried by said main frame normally having butt engagement with and actuating said power transmitting member on the feeder pile frame whereby when said feeder pile frame is moved away from said main frame said power transmitting members 110 automatically disengage each other in a movement longitudinally of the main frame, and means for propelling said feeder pile frame. 115

5. In a printing press, the combination of a main frame, a feeder pile frame movable away from and toward said main frame to provide a continuous space between said frames for "make ready", a plurality of shafts carried by said feeder pile frame, gears carried by one of said shafts, pinions carried by another one of said shafts and meshing with said gears, a member secured to one of said shafts through which power 125 130

may be applied thereto, and racks on the floor with which said gears may mesh for propelling said feeder pile frame.

6. In a printing press, the combination of a main frame, a feeder pile frame movable away from and toward said main frame to provide a continuous space between said frames for "make ready", a plurality of shafts carried by said feeder pile frame, 5 gears carried by one of said shafts, pinions carried by another one of said shafts 10

and meshing with said gears, a member secured to one of said shafts, through which power may be applied thereto, racks on the floor with which said gears may mesh for 15 propelling said feeder pile frame, and supporting wheels carried by said frame for guiding the movements of said feeder pile frame.

Signed at Chicago, Illinois, this 8th day 20 of April, 1924.

JOSEPH R. BLAINE.
